UNITED STATES PATENT OFFICE.

FRANCIS V. PHILLIPS, OF CHICAGO, ILLINOIS, ASSIGNOR TO THE CHICAGO SASH PULLEY COMPANY, OF SAME PLACE.

MORTISING-MACHINE.

SPECIFICATION forming part of Letters Patent No. 399,435, dated March 12, 1889.

Application filed April 15, 1887. Serial No. 234,899. (No model.)

To all whom it may concern:

Be it known that I, FRANCIS V. PHILLIPS, of Chicago, in the county of Cook and State of Illinois, have invented certain new and useful 5 Improvements in Mortising-Machines; and I do hereby declare that the following is a full, clear, and exact description thereof, reference being had to the accompanying drawings, and to the letters of reference marked thereon, 10 which form a part of this specification.

This invention relates to an appliance intended to be used upon mortising-machines for the primary purpose of controlling or 15 gaging the length of the mortise, and which, as preferably constructed, not only gages the length of the mortise, but also holds the piece being mortised down to the bed against the lifting tendency of the chisel.

The invention consists in the matters here- 20 inafter described, and pointed out in the appended claims.

The accompanying drawings illustrate three 25 of many practicable forms in which my invention may be embodied.

25 Figure 1 is a central vertical section taken longitudinally through the slot of a guide-plate and through the slide which works therein, together with a side view (broken) of the bed and of the strip being mortised. Fig. 30 2 is a top view of the matters shown in Fig. 1. Fig. 3 is a central vertical longitudinal section of a slotted base-plate, a slide working thereon, and a cam-lever for compressing the clamp-jaws. Fig. 4 is a top view of the clamp- 35 ing-jaws shown in Fig. 3. Fig. 5 is a side elevation, partially in a central vertical section, of a guide-plate and slide, showing another form of clamp device and stop for limiting the movement of the slide. Fig. 6 is a 40 sectional plan view of the parts shown in Fig. 5, taken on line $x-x$ of the latter figure.

A in all of the figures represents a guide-plate for a slide, which guide-plate is secured to the bed of a mortising-machine, (represented at 45 A'.). Said guide-plate A is shown as having a central longitudinal slot, a, having lateral rabbets or recesses a' on both sides in the under side of the plate. The slot is limited at both ends by cross-bars of the plate, or equiv-

alent means, to restrict the range of move- 50 ment on the part of the slide.

B is a slide fitted to the margins of the slot of the guide-plate A in a familiar manner.

C, Figs. 1 to 4, is an adjusting-screw 55 threaded through the outer cross-bar of the guide-plate and arranged to run in the direction of the slot, whereby it may serve as a stop for limiting the range of movement of the slide B.

C', Figs. 5 and 6, is a plate adjustably attached to the guide-plate, and serving as a stop for the slide B in place of the adjusting-screw C. An adjustable stop may of course be provided at each end of the slot of the 60 guide-plate, if desired. 65

Above the guide-plate the slide B is provided with some suitable means for engaging the strip of wood which is to be mortised, so that the slide will be drawn along with the strip or "stuff" as the latter is moved upon 70 the bed A' beneath the mortising-chisel C, and so that the slide, thus engaged with the stuff, will arrest the latter when the slide reaches the end of its movement in the slot of the guide-plate A. I prefer that such 75 engaging means shall be in the nature of a clamp calculated to hold the stuff down to the bed as well as to limit its movement. To this end, B' is a fixed lower jaw, and B² is a movable upper jaw, between which the end 80 of the stuff may be grasped.

In Figs. 1 and 2 the upper jaw, B², is in the form of a screw-threaded nut fitted to the screw-bolt b, which rises from the slide B. In this instance the slide B is of T shape and 85 the lower jaw, B', is in the form of a washer placed about the screw-bolt b.

In Figs. 3 and 4, b' is a plain post rising from the slide B, having a movable jaw, B², fitted to slide thereon like the movable jaw 90 of a monkey-wrench upon the shank, and B³ is a cam-lever pivoted at b² to the upper end of the post b' above and bearing upon the upper jaw, B². This or some equivalent adaptation of a cam is mechanically preferable to 95 the simple screw shown in previous figures as being quicker in its action than the ordinary screw. In this instance the lower jaw,

B' , is formed by the top surface of the slide itself. A spring, b^3 , is shown in position to raise the movable clamp-jaw B^2 when the cam is retracted.

5 In Figs. 5 and 6, B^4 is a rigid post or standard attached to the slide B , and provided with a horizontal arm, b^5 , at its upper end. B^5 is a screw threaded in the arm b^5 and carrying the upper clamp-jaw, B^2 . The screw 10 B^5 is provided with a crank or hand wheel, B^6 , whereby the screw may be turned for actuating the upper clamp-jaw.

When the stuff D is seized between the jaws B' and B^2 , the latter manifestly holds 15 that end of the stuff down to the bed of the machine against the lifting action of the chisels (seen at E) when rising out of the mortise after the down-cut, and when, as in the particular case of window-stiles the stuff is being 20 mortised to receive sash-cord guides, the mortise is near the end of the stuff, this clamp is practically all that is needed to enable the operator to keep the work to the machine-bed. If this clamping effect is not needed in 25 the appliance, but only such engagement of the slide with the stuff as will insure the regulation of the length and position of the mortise, then a single sharp spur, as b^4 , (shown in dotted lines of Figs. 1 and 4,) or a similar 30 device, may be provided on the slide to penetrate the stuff or stile under hand or other pressure, and the screw or post and clamping-jaws may be omitted.

In Figs. 4 and 5 the slide B consists of a 35 plate provided with opposite guide-grooves, b^6 b^6 , and the cross-bar a^2 of the guide-plate at one end of the latter is depressed below the end of the side margins of the slot a , which side margins form the guides for the 40 plate in such manner that the slide may be engaged with the guide-plate by thrusting it over the said cross-bar a^2 . In this instance the bar C' , forming the stop for the slide, is secured by a screw or screws, c , to the cross-bar a^2 , the said bar C' being provided with a 45

plurality of screw-holes, c' , to allow an adjustment of the bar longitudinally of the guide-plate.

The adjusting screw or screws C , bar C' , or other forms of adjustable stop or stops, may 50 be employed if the work requires provision for a variation in the length or position of the mortises within certain limits.

If the appliance is secured to the surface of the bed, a supplemental bed-piece, A^2 , will 55 be secured upon the bed to raise the stuff into position to enter the jaws or rest upon the slide.

I claim as my invention—

1. In combination, the horizontal table for 60 supporting the work, the slotted plate having guideways, a movable part fitted to said slotted plate and adapted to engage with the material, and a stop supported by the plate in direct line with the movable part, for limiting 65 its movement, substantially as described.

2. The combination, in a mortising-machine, of a stationary work-supporting table, a slotted guide-plate secured thereto, a slide, as B , engaging said guide-plate and movable thereon, a clamp carried by the slide B for engaging the material to be operated upon, and an adjustable stop passing through the end of the slotted guide-plate in the path of the slide B , whereby the movement of the work is limited, all substantially as described. 70

3. In combination, a table for supporting the work, a cutting-tool, guideways on said table, a movable plate adapted to said guideways, a clamp carried by said movable plate 80 for engaging the top of the work, and a spur, b^4 , on said plate adapted to engage with the work, all substantially as described.

In testimony that I claim the foregoing as my invention I affix my signature in presence of 85 two witnesses.

FRANCIS V. PHILLIPS.
